UNITED STATES PATENT OFFICE

NELS JENSEN, OF GRASS VALLEY, CALIFORNIA

SUNSHADE

Application filed May 16, 1928. Serial No. 278,173.

This invention relates to sun shades, and especially that type employed in conjunction with the windows of an automobile, or the like. The objects of the present invention is to generally improve and simplify the construction and operation of shades of the character described; to provide a shade and a support therefor which is adjustable to windows of varying width; to provide a shade and a support which is adapted to be attached to the inner side of a window and parallel therewith, so that the window may be opened or closed without interference with the shade; to provide a shade which may be swung outwardly from the window to assume any angular position desired, and which also permits substantial closing of the window when the shade is so extended; to provide means for frictionally securing the shade when in an angular extended position, and further to provide means for positively maintaining the shade against accidental release when extended, and for maintaining a constant tension on the shade to prevent flapping and noise when driving.

The shade is shown by way of illustration in the accompanying drawings, in which:

Fig. 1 is a perspective view of a portion of an enclosed type of automobile, such as a sedan or the like, showing the attachment of the sun shade.

Fig. 2 is a vertical section of the front door of an automobile, taken on line 2—2 of Fig. 1, said view showing the method of attaching the sun shade to the door.

Fig. 3 is an enlarged detailed sectional view of one of the supporting brackets, and a pivot rod whereby the extension brackets are secured.

Fig. 4 is a perspective view, showing the inner side of the door of an automobile, said view showing the position of the sun shade and the brackets supporting the same.

Fig. 5 is a perspective view of one of the supporting brackets, said view also showing a portion of one of the extension brackets and one of the friction springs securing the same.

Fig. 6 is a perspective view of one end of the shade roller.

Figs. 7 and 8 are perspective views respec-

tively of the extension bracket supporting rod, and socket therefor.

Figs. 9 and 10 are perspective views respectively of the shade cloth stick, and the socket supporting the same.

Fig. 11 is a perspective view of one of the extension brackets.

Fig. 12 is a perspective view of a washer employed in conjunction with the extension brackets shown in Fig. 11.

Fig. 13 is a perspective view of the supporting bracket which supports the rounded end of the shade roller.

Fig. 14 is a perspective view of one of the friction spring arms.

Automobiles of the enclosed type, such as sedans, coupes, etc., are usually provided with one or more side doors, which are opened for entrance or exit from the car. Doors of such cars are usually provided with sliding windows, which may be opened or closed for ventilation and circulation of air. Windows of this character usually consist of a section of plate glass, such as shown at A, which are supported in a frame which may be raised and lowered by mechanism, not here illustrated. The plate glass window is mounted in guideways, such as shown at B, formed in opposite sides of the door, and these guideways are lined with felt strips or the like, to prevent rattle. The problem of mounting a sun shade in the window opening of an automobile door is not a simple one, as the shade, together with its support and operating mechanism must be

neat and compact, it must assume as little space as possible and it must not interfere with the opening and closing of the window.

The sun shade forming the subject matter of the present application is simple and neat in appearance, it may be rigidly secured to the inner surface of the door, and it does not interfere with the opening and closing of the window.

The sun shade, here illustrated, consists of a shade cloth C, and a spring actuated roller D, upon which it may be wound in the manner of an ordinary shade cloth, when not in use. Any desired form of shade cloth may be employed. It is attached to the sur-

face of the shade roller D, in the usual manner, and the shade roller is provided with the usual internal spring mechanism, which is wound when the shade cloth is extended, so as to be placed under sufficient tension to rewind the shade cloth when it is not required. This mechanism is all common and illustration thereof is thought unnecessary.

The shade roller is, in this instance, supported in a pair of brackets, such as shown in Figs. 5 and 13. These brackets are substantially identical in construction. They consist of side and top plates, such as indicated at 2 and 3, bent at right angles to each other. The side plates are provided with right angular flanges or tongues, and the top plates 3 are similarly provided with tongues or flanges 5, the tongues or flanges 4 and 5 being adapted for insertion in the slotted guideways B of the door, so as to position and assist in retaining the brackets shown in Figs. 5 and 13. The brackets are placed in the window opening as shown in Figs. 2, 3 and 4, and they are there secured by passing screws 6 through perforations 7, formed in the upper plates 3 of the respective brackets. The end plates 2 of the brackets are slightly spaced with relation to the sides of the window opening, and the purpose of this spacing will later be described.

One of the brackets, such as shown in Fig. 5 is provided with a slot-like opening 8, for the reception of the flattened pin 9 of the shade roller, while the opposite bracket is merely provided with a rounded hole for the reception of the shade roller pin. The free end of the shade cloth is, in this instance provided with a shade stick generally indicated at E, which is grasped when it is desired to extend or retract the same. The shade stick employed in this instance consists of a rod 10—see Fig. 9, which is adapted to receive a socket member 11 at each end. The socket member as shown in Fig. 10, is provided with a socket or recess to receive the end of the rod 10, and is provided with a head 12, and a reduced portion 13, which is adapted to be received by a slot or guideway 14, formed in the extension bracket 15—see Fig. 11. There are two of these brackets, one at each end of the shade roller, and they are pivotally attached to the brackets shown in Figs. 5 and 13, as will now be described.

Formed in the side section 2 of each bracket, is a journal opening 16, and journaled therein is a short section of hexagon rod, such as shown at 17, see Figs. 3 and 8. Secured to the inner end of the hexagon rod or pin 17, by riveting or the like, is a friction spring arm 18, see Figs. 3, 5 and 14. Secured to the opposite end of the hexagonal rod or pin is a sleeve or socket member 19, and this is adapted to receive a cross rod 20, see Figs. 3 and 7. The sleeve or socket member 19 is hexagonal, at least on its interior

surface to slip over the rod 17, and it is riveted or otherwise secured thereto, as indicated at 21. The upper ends of the extension brackets 15 are slightly offset, as shown at 22, see Figs. 3 and 11, and the offset ends are provided with hexagonal perforations 23, to permit them to be slipped over the pins or rod section 17. A friction washer 24, see Figs. 3 and 12, is interposed between the side plate 2 of the bracket, and the extension bracket 15, and this washer cooperates with the spring arm 18, to frictionally secure the extension bracket arm 15, in any angular extended position desired, see, for instance, the dotted line positions shown at 25 and 26 in Fig. 2.

From the foregoing description it should be noted that the shade stick 10, and the rod 20, are both supported in socket members indicated at 11 and 19 respectively. This is important as it permits the shade to be installed in windows of varying width—that is, the rods 10 and 20 may be cut to desired length to suit the particular window in which it is to be installed, and they are then merely inserted in the socket members 11 and 19. In actual operation, hexagon pins are inserted in the respective brackets shown in Figs. 5 and 13. The spring arms 18 are attached and riveted over. The friction washers 24 are then applied on the opposite side, and so are the extension bracket arms 15. The sleeves or socket members 19 are next applied and riveted, or otherwise secured and the assembly is then completed. This, of course, is all done at the factory and the brackets, when so completed, are sold to the distributors or retailers together with the shade roller D. These are provided in different lengths. Long rods, such as shown at 10 and 20, may at the same time be supplied and these are then merely cut to the desired length when installation is made.

Everything required, is accordingly standard with the exception of the shade roller, and this may be provided in different lengths, to suit windows of different widths.

In actual operation, when installing the sun shade, the rods 10 and 20 are cut the proper length and placed in the socket members 11 and 19 respectively. The shade roller is placed between the brackets and the brackets are secured on the inside of the window opening by inserting the screws 6. This completes the installation and the shade is ready for use.

It will be noted that the entire installation is made interior of the plate glass window, indicated at A, see Figs. 2 and 4.

If it is desired to lower the shade when the window is closed, it is only necessary to grasp the shade stick E and to pull it downwardly. When so pulled, the headed ends 12 of the socket members 11 will be guided in the slots 14 of the extension bracket arms 15.

These slots are hook-shaped at their lower ends, as shown at 14^a—in other words, the shade is lowered until the headed members 12, and the reduced ends 13 of the socket members engage the hooks 14^a. They will here secure the shade against accidental release, and the spring in the shade roller will maintain the shade cloth under sufficient tension to prevent flapping and noise when driving.

10 The shade cloth may be pulled downwardly inside the window A when the extension bracket arms 15 assume the full line position shown in Fig. 2. On the other hand, if it is desired to extend the shade to assume an angular position, such as indicated at 25, or 26, it is first necessary to lower the window and then to swing the shade cloth, together with the extension bracket arms 15, outwardly. The shade cloth and the extension bracket arms are here frictionally secured by the spring arms 18 and the washers 24 cooperating therewith.

15 After the shade has been extended to assume an angular position exterior of the window opening, it is possible to substantially close the window A. That is, it may be raised up into contact with the extension bracket arm or substantially so, this being a great advantage, as it is often desired to exclude both wind and rain when driving under certain conditions, and still retain the benefit of having the shade exterior of the window.

20 In the first part of the specification it was stated that a slight spacing was provided between the sides of the brackets shown in Figs. 5 and 13, and the sides of the window opening. This spacing is clearly shown at 35, see Fig. 3. This spacing is necessary, as free movement of the spring arms 18 is thereby permitted. These springs, together with the washers 24, take up wear, and at all times exert sufficient friction to prevent rattle and to secure the extension bracket arms 15 whenever extended. The offset 22, at the upper ends of the extension bracket arms, as shown in Fig. 11, is approximate to the thickness of the washers 24. The extension bracket arms thus lie substantially flush with the inner surface of the side plates 2 of the brackets, and a neat, compact structural arrangement is provided.

25 Having thus described my invention, what I claim and desire to secure by Letters Patent is:—

30 1. A device of the character described comprising a pair of interspaced bracket members, a spring actuated shade roller journalled between said brackets, a rod pivotally secured between the brackets and to one side of the roller, friction means resisting rotation of said rod, a pair of flat arms secured at their upper ends to said rod, one adjacent each bracket, said arms being slotted substantially from end to end and the slots terminating in hook-shaped notches at their lower ends, a shade

cloth secured to the roller, and a shade stick secured to said cloth, said shade stick extending beyond each end of the shade cloth and projecting through the slotted arms to be guided thereby, said projecting ends of the shade stick adapted to enter the hook-shaped notches at the lower ends of the arms to secure the shade cloth when unrolled. 70

2. A device of the character described comprising a pair of interspaced bracket members, a spring actuated shade roller journalled between said brackets, a longitudinally adjustable rod pivotally secured between the brackets and to one side of the roller, friction means resisting rotation of said rod, a pair of flat arms secured at their upper ends to said rod, one adjacent each bracket, said arms being slotted substantially from end to end and the slots terminating in hook-shaped notches at the lower ends of the arms, a shade cloth secured to the roller, a shade stick secured to the shade cloth, said shade stick extending beyond each end of the shade cloth and projecting through the slotted arms to be guided thereby, said projecting ends of the shade stick adapted to enter the hook-shaped notches at the lower ends of the arms to secure the shade cloth when unrolled, and means permitting longitudinal adjustment of the shade stick. 85

3. In a device of the character described a bracket, a rod pivotally mounted thereon, a spring arm secured to one end of the rod, said arm having a free end which frictionally engages the face of the bracket, an arm secured at its upper end to said rod, and a socket member on said rod, said rod, socket member and arm adapted to pivot with relation to the bracket and said pivotal movement being resisted by the free end of the spring arm moving over the face of the bracket. 100
